FIG. 1 is a side perspective view from the front of a left side light assembly of an exterior surface configuration of an automobile front light assembly according to our novel design; and,

FIG. 2 is a perspective view from above the assembly of FIG. 1.

The novel design also includes an embodiment of a right side light assembly which is mirror symmetrical to the embodiment of FIGS. 1 and 2 and therefore not separately illustrated.

The dash line showing is only for showing the surrounding environment and is not a part of the claimed design.
